UNITED STATES PATENT OFFICE.

CHARLES T. RICHMOND AND MARCUS H. MOFFETT, OF CLEVELAND, OHIO,
ASSIGNORS TO THE NATIONAL CARBON COMPANY, OF CLEVELAND,
OHIO, A CORPORATION OF NEW JERSEY.

VOLTAIC CELL.

SPECIFICATION forming part of Letters Patent No. 733,751, dated July 14, 1903.

Application filed May 25, 1903. Serial No. 158,608. (No model.)

To all whom it may concern:

Be it known that we, CHARLES T. RICHMOND and MARCUS H. MOFFETT, citizens of the United States, residing at Cleveland, in the county of Cuyahoga and State of Ohio, have invented a certain new and useful Improvement in Voltaic Cells, of which the following is a full, clear, and exact description, reference being had to the accompanying drawings.

The object of the invention is to produce a voltaic cell the parts of which will be cheaply constructed and easily and quickly assembled in operating relationship.

15 The invention may be summarized as consisting in the combination of parts herein-after described, and pointed out definitely in the claims.

In the drawings, Figure 1 is a central vertical sectional view of the cell embodying the invention. Fig. 2 is a transverse sectional view on the line 2 2 of Fig. 1, and Fig. 3 is a perspective view of the dome-shaped nut by which the carbon electrode is secured to the cover.

25 Referring to the parts by letters, A represents a cover which is made of insulating material and is adapted to rest on top of the jar, which is shown in dotted lines. A substantially central hole a is formed through this cover, as is also a second hole a' . (Shown in Fig. 2 and indicated by dotted lines in Fig. 1.) On the under side of this cover is an annular downwardly-extended flange a^2 , which is concentric with the hole a .

B represents the carbon electrode in the form of a hollow cylinder having external longitudinal grooves. The top of this carbon electrode is squared off—in other words, is in a plane substantially at right angles to the axis of the cylinder. Projecting upward from this squared-off end is a boss b , which passes through the hole a in the cover. A metallic screw C is embedded in this boss and extends upward therefrom. D represents a dome-shaped nut, which screws onto this screw C , and its lower edge, which is of greater diameter than the hole a , bears upon the top of the cover, and thereby the squared-off upper

end of the carbon electrode is drawn tightly 50 against the under side of the cover, wherefore it will keep a position at right angles thereto. This dome-shaped nut serves the additional purpose of substantially sealing the hole a .

E represents the zinc electrode, which is in 55 the usual form of a split cylinder, and it is of such diameter as to snugly embrace the flange a^2 of the cover. The top edge of this cylinder is all in a plane which is substantially at right angles to the axis of the cylinder. This 60 zinc electrode is provided with a threaded stem e , which extends up through the hole a' in the cover, and a nut f , which screws thereon, holds the upper end of the zinc electrode against the under side of the cover embracing 65 the flange a^2 , wherefore this zinc also stands at substantially right angles to the cover, and therefore at all points the same distance away from the external surface of the electrode B, and this makes it unnecessary to hold these 70 two electrodes apart by rubber plugs or rings, as is customary in many constructions. The carbon electrode is hollow and is open at the lower end only, and this opening is closed by a removable plug G , which screws into the 75 same.

Having described our invention, we claim—

1. The combination of a cover of insulating material in which are the two holes a , a' , and which has on its under side an annular flange 80 a^2 , with a carbon electrode having a squared-off upper end, and a boss projecting upward from the same through the hole a of the cover, a screw C embedded in and projecting upward from said boss, a dome-shaped nut which 85 screws upon said screw and whose lower edge bears upon the top of the cover around said hole a , substantially as specified.

2. The combination of a cover of insulating material in which are two holes a , a' , and which 90 has on its under side an annular flange a^2 , with a carbon electrode having a squared-off upper end, and a boss projecting upward from the same through the hole a of the cover, a screw C embedded in and projecting upward from 95 said boss, a dome-shaped nut which screws upon said screw and whose lower edge bears upon the top of the cover around said holes a ,

a' , a zinc electrode in the form of a split cylinder which embraces the flange on the cover and whose upper end bears against the upper side of the cover, said zinc electrode having a 5 threaded stem which extends upward through the hole a' of the cover and a nut F which screws onto said threaded stem, substantially as specified.

3. The combination of a cover of insulating 10 material in which are two holes a, a' , and which has on its under side an annular flange a^2 , a carbon electrode having a squared-off upper end, and a boss projecting upward from the same through the hole a of the cover, and a 15 screw C embedded in and projecting upward

from said boss, with a dome-shaped nut which screws upon said screw and whose lower edge bears upon the top of the cover around said hole a , said electrode having a central hole extending upward from its lower end and a removable screw-plug for closing the lower end of said hole, substantially as specified. 20

In testimony whereof we hereunto affix our signatures in the presence of two witnesses.

CHARLES T. RICHMOND.
MARCUS H. MOFFETT.
